BAND BRAKE

Reynold F. Gamundi, Mayfield Heights, Ohio,
assignor to Eaton Manufacturing Company,
Cleveland, Ohio, a corporation of Ohio

Application December 17, 1949. Serial No. 133,639

4 Claims. (Cl. 188—137)

1

This invention relates to band brakes and more particularly to two-way band brakes primarily, though not exclusively, useful for braking and locking rotary drums in automatic transmissions or the like.

The object of the invention is the provision of an improved two-way band brake which is adapted for braking in either direction of rotation, wherein substantially the entire effective length of the brake band is available for braking in either direction of rotation. In general, this is accomplished by providing a magnetic brake drum and a band coiled around the drum with electromagnetic shoes attached to the band at the ends of the band. The shoes are adapted magnetically to cling to the drum upon being energized. An anchor pin is fixed with respect to the drum extending longitudinally and outward of the periphery of the drum. The shoes have ears extending radially outward on opposite sides of the pin, the ears being spaced apart a distance greater than the width of the pin. With this arrangement, the entire length of the band between shoes is effective for braking in one direction or another of rotation simply by causing the shoes to cling to the drum, as will be made clear. Other features will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which one of various possible embodiments of the invention is illustrated.

Fig. 1 is a diagrammatic view illustrating the basic principles of the invention:

Fig. 2 is a side elevation of a brake embodying the invention, with parts broken away and shown in section; and.

Fig. 3 is a transverse section taken on line 3-3 of Fig. 2, with parts broken away and shown in section.

Similar reference characters indicate corresponding parts throughout the several views of the drawing.

Fig. 1 diagrammatically illustrates the basic principle of the operation of the invention. A rotary drum member is shown at A and a band anchoring member at B. These are relatively rotary. Usually, the drum member is rotary and the band anchoring member stationary. A friction strap or band C is loosely coiled around

2

the drum and has both its ends anchored (with play) to the anchoring member at D. At E are shown two shoes attached to the band at spaced points along its length. Means is provided whereby the shoes may be caused to cling to the drum. For example, the drum may be made of magnetic material and each shoe an electromagnet adapted magnetically to cling to the drum upon being energized or excited. With this arrangement, assuming the drum to be rotary and the band anchoring member stationary, the entire portion of the length of the band between the two shoes is effective for braking upon rotation of the drum in either direction.

15 Referring now to Figs. 2 and 3 of the drawing, which illustrate a practical embodiment of the invention, there is shown at 1 a casing constituting a brake housing. Rotary in the housing is

20 a brake drum 3, which is made of magnetic material such as iron or soft steel, and which has a cylindric periphery. The drum is shown as fixed on a shaft 5 journalled in bearings (not illustrated) in the end walls of the housing 1. A lined flexible bellows 6 is shown in the housing 1.

25 lined flexible brake band 7 is helically coiled around the drum. An electromagnetic shoe 9 is attached at 11 to one end of the band. A second electromagnetic shoe 13 is attached at 15 to the other end of the band. The band is coiled in counterclockwise direction from shoe 13 to shoe 30 9 as viewed in Fig. 3.

Each of the shoes 9 and 13 is also composed of magnetic material such as iron or soft steel, formed to fit against the periphery of the drum and to contain a magnetizing coil 17.

35 and to contain a magnetizing coil 17. As shown, each shoe has an outer wall 19 with its outside face 21 curved on an arc centered in the axis of the drum, and side walls 23 and a central wall 25 extending from the outer wall toward the drum with their inner edges curved as indicated at 40 27 to fit against the peripheral flange 29.

27 to fit against the periphery of the drum. The central wall 25 forms a pole around which is fitted the coil 17. The side walls project somewhat outward of the outer wall 19 and their outer edges are curved, as indicated at 29, on an arc centered in the axis of the drum.

At 31 is shown an anchoring member which consists of a pin extending longitudinally of the housing and located outward of the periphery of the drum. The pin is fixed in a pair of longitudinally spaced bosses 33 formed on the interior of the peripheral wall of the housing. The shoes 9 and 13 are located between the pin and the drum and are spaced apart longitudinally with respect to the housing. The pin extends between radially outwardly extending ears 35 and 37 on

shoe 9 and between radially outwardly extending ears 39 and 41 on shoe 13. Ears 35 and 37 on shoe 9 are spaced apart on the arc of the outer face of the shoe a distance greater than the diameter of pin 31 so that the shoe 9 is adapted for movement in an arc around the axis of the drum as limited by the engagement of the ears with the pin. Similarly, ears 39 and 41 on the shoe 13 are spaced apart on the arc of the outer face of the shoe a distance greater than the diameter of pin 31 so that the shoe 13 is also adapted for movement in an arc around the axis of the drum, as limited by the engagement of the ears with the pin. The ears on the shoes are formed as integral extensions of the side walls of the shoes. The ears 35 on the shoe 9 and the ears 39 on the shoe 13 are the end ears of the shoe and brake band assembly.

The brake band 7 is of such length that, with the band loosely coiled around the drum, ears 35 on shoe 9 engage the pin 31 and ears 39 on shoe 13 engage the pin, as shown in Fig. 3. Thus, while shoe 9 is anchored against clockwise movement as viewed in Fig. 3 and anchors the respective end of the band against clockwise movement as viewed in Fig. 3, it may move counterclockwise within the limit imposed by ears 37, and while shoe 13 is anchored against counterclockwise movement by the ears 39 and anchors the respective end of the band against counterclockwise movement, it may move clockwise within the limit imposed by ears 41.

The shoes are lightly biased against the periphery of the drum by spring-loaded rollers 43 which bear against the outside arcuate faces 21 of the outer walls 19 of the shoes. Rollers 43 are mounted on shafts 45 supported in bearing members 47 on studs 49. Studs 49 slide in radial sockets 51 formed on the interior of the wall of the housing and are biased radially inward by compression springs 53 in the sockets, the latter reacting from the bases of the sockets against the ends of the studs.

The magnetizing coils 17 of the shoes 9 and 13 are adapted to be energized or excited through suitable leads (not shown). Normally, both coils are deenergized and the drum rotates freely within the brake band 7, the band being loose and shoes 9 and 13 offering no substantial impedance to rotation. Assuming that the drum is rotating counterclockwise as viewed in Fig. 3, and it is desired to stop it, both coils 17 are energized. The shoe 9 thereupon magnetically clings to the drum and is carried around with the drum counterclockwise as indicated by the arrow F in Fig. 3, thereby initiating tightening of the brake band.

This action is permitted by the play in the connection of the shoe 9 to the anchor pin 31, and is followed by a frictional servo action occasioned by the friction between the brake band and the drum which causes the brake band tightly to grip and lock the drum against rotation. The final locking action of the band is not dependent upon the magnetic clinging of the shoe 9 to the drum, this magnetic clinging only initiating the tightening of the band. While, as above described, the coil 17 for shoe 13 is here energized, this is of only minor effect in braking. If desired, to stop counterclockwise rotation of the drum, only the coil for shoe 9 need be energized. When the shoes are deenergized, the brake band is released.

Assuming that the drum is rotating clockwise as viewed in Fig. 3, and it is desired to stop it,

both coils 17 are energized. The shoe 13 thereupon magnetically clings to the drum and is carried around with the drum clockwise, as indicated by the arrow G in Fig. 3, thereby initiating tightening of the brake band. This action is permitted by the play in the connection of the shoe 13 to the pin 31, and is followed by a frictional servo action occasioned by the friction between the brake band and the drum which causes the brake band tightly to grip and lock the drum against rotation. The final locking action of the band is not dependent upon the magnetic clinging of the shoe 13 to the drum, this magnetic clinging only initiating the tightening of the band. As before, while coil 17 for the shoe 9 is here energized, this is of only minor effect in braking. If desired, to stop clockwise rotation of the drum, only the coil for shoe 13 need be energized. When the shoes are deenergized, the brake band is released.

Thus, the above-described arrangement is adapted to brake the drum in either direction of rotation. An important feature of the construction is that the same entire effective length of the brake band is effective for braking in either direction.

While in the above-described embodiment of the invention, the brake drum 3 is rotary and the brake band anchoring member is stationary, it will be understood that this relationship may be reversed. That is, the brake drum may be stationary and the brake band anchor rotary. Moreover, it is also contemplated that the invention may be applied in a system wherein both the drum and the brake band anchor rotate, in which event, when the electromagnetic shoes are energized, the drum and brake band anchor will be clutched together and brought to the same speed. In this event, the device might be called a clutch, and the term "brake" is to be understood to refer to such a system, because the action is in fact a braking action wherein one element is brought to a relatively stationary relationship with respect to the other when the brake is set.

In view of the above, it will be seen that the several objects of the invention are achieved and other advantageous results attained.

As many changes could be made in the above constructions without departing from the scope of the invention, it is intended that all matter contained in the above description or shown in the accompanying drawing shall be interpreted as illustrative and not in a limiting sense.

I claim:

1. A brake comprising a housing, a magnetic brake drum rotary in the housing, an anchor pin fixed in the housing extending longitudinally and located outward of the periphery of the drum, a lined brake band coiled around the drum, and electromagnetic shoes attached to the band at its ends and located between the pin and the drum, the shoes being adapted magnetically to cling to the drum upon being energized, each shoe having ears extending radially outward therefrom on opposite sides of the pin, the ears being spaced apart a distance greater than the width of the pin.

2. A brake comprising a housing, a magnetic brake drum rotary in the housing, an anchor pin fixed in the housing extending longitudinally and located outward of the periphery of the drum, a lined brake band coiled around the drum, and electromagnetic shoes attached to the band at its ends and located between the pin and the drum, the shoes being adapted magnetically to cling to the drum upon being energized, each shoe

having an inner curved face adapted to fit against the periphery of the drum and an outer face curved on an arc centered in the axis of the drum and ears extending radially outward therefrom on opposite sides of the pin, the ears being spaced apart a distance greater than the width of the pin.

3. A brake comprising a housing, a magnetic brake drum rotary in the housing, an anchor pin fixed in the housing extending longitudinally and located outward of the periphery of the drum, a lined brake band coiled around the drum, and electromagnetic shoes attached to the band at its ends and located between the pin and the drum, the shoes being adapted magnetically to cling to the drum upon being energized, each shoe having an inner curved face adapted to fit against the periphery of the drum and an outer face curved on an arc centered in the axis of the drum and ears extending radially outward therefrom on opposite sides of the pin, the ears being spaced apart a distance greater than the width of the pin, and spring-loaded rollers biasing the shoes toward the drum.

4. A brake comprising a rotary magnetic brake

drum, an anchor pin fixed with respect to the brake drum extending longitudinally thereof and located outward of the periphery of the drum, a brake band coiled around the drum, and electromagnetic shoes attached to the band at its ends and located between the pin and the drum, the shoes being adapted magnetically to cling to the drum upon being energized, each shoe having ears extending radially outward therefrom on opposite sides of the pin, the ears being spaced apart a distance greater than the width of the pin.
